CYLINDRICAL MILLING TOOL

Application filed June 28, 1924. Serial No. 722,916.

This invention relates to cylinder grinders of an improved construction and arrangement particularly adapted to be operated by a portable motor for the grinding or resizing of the cylinder bores of automobile motor blocks. The device is of an improved design wherein the supporting members or trays, carrying the grinding or honing stones are supported to be conveniently and readily adjustable with a relatively wide range of movement for the initial adjustment of the tool to cylinder bores of different diameter.

Important features thereof comprise means for rigidly securing the supporting or tray members in their adjusted position, such means being desirably located at the upper portion of the tool and of such construction as to materially facilitate making the adjustment as required. My present improvements further embody special features of construction as related to the mounting of the tray members wherein the tray members in their adjusting movement are moved radially in unison while maintaining their proper angular relation and whereby in their innermost positions they will assume a nesting or overlying relation thereby providing a wider range of adjustment and desirable structural compactness. The present structure is further especially designed to incorporate therewith important features illustrated in my co-pending application Ser. No. 610,617 as related to the supporting arrangement for the honing stones whereby the latter are arranged to act under a yielding pressure while maintaining at all times parallelism of their acting surfaces. My present improvements further embody the desirable feature and structural arrangement wherein the honing stones are supported to be acted upon by an outwardly directed and yielding pressure and wherein the adjustment for size or diameter of the bore is accomplished without affecting the pressure means whereby the latter will be uniform in its action in the varied position and adjustment for size. A further and valuable feature of the improved structure consists in the normal manner of supporting the stones whereby they will have a tilted relation to the surface to be acted upon

with the result that the cutting or honing action will be performed by the forward edge of the stone whereby a material increase in effectiveness is obtained in addition to other important advantages.

The described and other features and advantages of my invention will be understood by reference to the accompanying drawing wherein like reference characters are applied to the corresponding parts in the several views.

Referring to the drawing:

Fig. 1 is a view in side elevation illustrating a desirable embodiment of the features of the present invention with the parts shown in their innermost position of adjustment.

Fig. 2 is a central, vertical, sectional view thereof with the parts shown in expanded position.

Fig. 3 is a sectional plan view with the parts shown in the innermost position corresponding to Fig. 1 and taken on line 3—3 thereof.

Fig. 4 is a similar view showing the parts in the position of adjustment corresponding to Fig. 2 wherein one of the tray members is shown in section.

In the approved construction as illustrated, 1 indicates a centrally positioned supporting shaft having its upper portion threaded at 2 and formed with upper and lower integral and circular bearing collars 3 and 4. The bearing collars 3 and 4 are provided with concentrically arranged and equi-distantly spaced circular apertures 5 within which are fitted and supported bearing rods or shafts 6—6 arranged vertically and in parallel relation. Upon each of the bearing shafts 6 there is pivotally mounted a carrier member or tray 7 of suitable form and length to support the grinding or honing stones indicated at 8. As shown the outer or body portions of the tray 7 are integrally formed with upper and lower arcuate arms 9 and 10 formed at their inner ends with apertured bearing collars 11 fitted to the shaft 6 whereby the trays are pivotally supported to swing about the bearing shaft 6 as an axis. The trays are accordingly adapted to assume positions of varied radial distance from the supporting member or

shaft 1 and means are provided to effect this adjusting movement operative to adjust the trays in unison and to constantly maintain the concentric relation of the several trays, four as shown, with respect to the shaft 1 or longitudinal axis of the tool.

In accordance with the present invention the means for effecting the circumferential or radial adjustment of the trays is arranged 10 to be operable by simple manipulation from the upper portion of the device with the result that this adjustment may with facility be made at varied stages of the operation. The adjusting mechanism here shown comprises 15 an adjusting member or disc member 14 of circular form having a knurled peripheral surface 15 and a central bearing aperture whereby it is rotatably fitted upon the shaft 1 and upon its lower surface it is formed 20 to receive equi-distantly spaced and concentrically arranged bearing studs 16—16. The studs 16 provide pivotal bearings for connecting links 17 which are each pivotally supported upon the studs 16 at their inner 25 ends and at their outer ends have pivotal bearing upon screw studs 18 threaded to integral bosses or extensions 20 of the respective carrier members or trays 7. In consequence of the symmetrical and concentric arrangement 30 of the pivotal points 2, 16 and 18 and the corresponding angular positioning and length of the connecting links 17, the arrangement is such that upon the rotation of the adjusting member 14 relative to the supporting shaft 3, it will simultaneously and uniformly swing the tray member 7 inwardly or outwardly to determine the effective diameter of the tool. The adjustment in unison as thus performed provides that in all 40 positions of adjustment the supporting trays shall be equally spaced with relation to each other and also with relation to their radial distance from the central longitudinal axis of the tool or of the supporting shaft 1. As 45 will be appreciated manipulation of the adjusting member 14 allows of very quickly adjusting the effective diameter of the tool within a wide range of movement and a wing clamping nut 22 is threaded upon the upper portion 2 of the supporting shaft and positioned to engage the adjusting member 14 to clamp the latter tightly against a shoulder 23 formed on the shaft 1 for rigidly securing the parts in adjusted position.

50 As will be noted, the adjusting lever 14 and the clamping nut 22, are arranged at the upper portion of the tool to be at all times accessible to the operator so that the manipulation of the adjusted parts is conveniently and easily accomplished. Upon the upper extremity of the supporting shaft 1, there is mounted a socket member 24 secured by the pin 25, this socket being designed to effect 55 flexible coupling connection with the lower end of a driving spindle 27, which may, at

its upper end, be adapted for connection with the chuck of a portable electric driving motor for rotatably connecting the lower end of the spindle 22 to the socket. The spindle is provided with a coupling pin 28 passed through an entry slot formed at the upper wall of the socket member and the socket is of a form to provide shoulders 26 opposed to the end portions of the coupling pin 28 to effect driving connection.

A further important feature of the present invention consists in the desirable form of the tray members and their supporting arrangement. As best shown in Figures 3 and 4 the supporting arms 9 and 10 of the tray members are of curvilinear form of an S contour whereby upon being moved into their extreme rearward position as illustrated in Fig. 3 clearance is provided for the bearing rods 6. This permits of the bottom or inner portions of the tray members assuming a position inwardly of the rods thereby to obtain a maximum range of adjustment. The arrangement whereby the supporting arms of the tray have a nesting or overlying relation is further instrumental in providing for the swinging movement of the trays in an arc of relatively large radius and from centers in close proximity to the axis of the supporting shaft 1 from which there is obtained the desirable result that the trays throughout their length of movement maintain a position substantially radial to the central longitudinal axis of the tool and in consequence maintain effective operating relation to the wall to be acted upon.

With the improved construction as described there is desirably associated the special means for supporting the stone elements to be acted upon by an outward spring pressure in the manner covered by my copending application Ser. No. 610,617, filed January 4, 1923. The type of support as therein disclosed provides for supporting the stones to be yielding against the influence of an outwardly acting spring pressure while at all times maintaining the accurate parallel relation of the stones considered lengthwise thereby to insure that the finished bore shall be of uniform diameter throughout its length. As a result the tool is operative to correct cylinder walls which have been worn to a tapered condition wherein the walls are inclined from parallel relation. In the construction as illustrated the central portion 30 of the rear wall of the tray or carrier member is inwardly extended, providing an elongated socket 31 to receive a pressure transmission plate or tension plate 32 which is pivotally or hingedly supported lengthwise and at one edge thereof by having its longitudinal edge fitted within a hinge slot or recess 33 formed in the side wall of the tray member and extending lengthwise thereof parallel to the longitudinal axis of the tool.

For retaining the plate 32 within the slot 33 the plate is provided with an enlarged aperture 35 to receive therein a securing screw stud 36 threaded to the inner or bottom wall 5 of the tray. The slot 35 and screw 36 are proportioned to allow of the required movement of the pressure plate while retaining the plate within the hinge slot. The outer or free edge of the pressure plate 32 has bearing engagement upon the underside of the honing stone 8 indirectly by engaging the channel plate 37 in which the stone is fitted. Within suitable socket depressions formed in the rear wall of the trays, coil springs 15 38-38 are arranged in position interposed between the bottom of the tray and the inner sides of the pressure plates 32 so as to exert an outward pressure against the latter. As best illustrated in Fig. 2 the end walls of 20 the stones are provided with enlarged pockets or recesses 39 engaging the retaining pin 40 and the retaining set screw 41 arranged to allow of the stones having a limited radial movement while retaining them within the 25 trays. It accordingly provides that the pressure plates 32 are supported and confined to move in a fixed plane under the influence of the compression springs bearing thereagainst and in consequence the radial movement 30 of the honing stones is governed so as to be uniform throughout their length and thereby maintain at all times the desired parallel or true vertical position of their active surfaces. This feature is of material 35 importance as related to the successful operation of the tool in the reborning of worn cylinders by insuring that the refinished bore shall have its walls accurately parallel or longitudinally of uniform diameter.

40 In accordance with a further feature of my invention the honing stones 8 are desirably supported within the carriers or trays 7 so as to be inclined or tilted with reference to the surface acted upon with the result that 45 the cutting or honing action is performed by the forward and outer longitudinal edge of the cutting stone. As a result thereof the pressure of the stone against the surface acted upon is concentrated and a more effective cutting or honing action is obtained. Structurally, this is accomplished, as best illustrated in Figure 4, by the improved arrangement whereby the honing stones 8 are fitted within metal channel members 8' directly 50 55 engaged by the tension plate 32 and proportioned to have a loose fit within the sockets of the tray members. To cooperate therewith the tension plates 32 are of such width as to engage the inside of the channel members 8' 60 65 to one side of the central axis thereof to effect the tilting of the stone to position it with one edge thereof outermost and to accordingly become the effective portion in the grinding operation. Considered with relation to 65 the direction of rotation of the tool, as indi- cated in Figure 4, the tilting of the stone is such as to bring the forward edge thereof into outermost position and in practice this is accomplished by proportioning the stone or its channel member to have a loose fit 70 within the tray socket with a clearance of about one thirty-second of an inch. As a result the desirable advantage of a more effective cutting surface is obtained and in addition chattering of the stones during the honing operation is eliminated and in consequence the honing may be performed as a dry operation without the use of lubricant. 75

In the operation it will be understood that the described construction permits of conveniently adjusting the effective diameter of the tool to the size of the bore to be refinished. This initial adjustment is effected by releasing the clamping nut 22 and rotating the manipulating member 14 thereby swinging 80 the respective trays in unison to determine the diameter of the tool or the radial position of the trays with relation to the bore after which the clamping nut is screwed down to rigidly clamp the parts in position. This 85 adjustment is such that the stones shall be compressed or moved inwardly against the influence of the spring actuated pressure plates 32 whereby the stones during the rotation of the tool within the bore shall act 90 outwardly against the cylinder walls under spring pressure to effect the grinding or honing of the surface. As will be readily understood the initial adjustment of the trays may be accomplished with the tool withdrawn 95 from the cylinder bore and the tool then inserted by pressing the stones inwardly. Incidental to the improved structure, as disclosed, this initial adjustment of the stones 100 with relation to the diameter of the bore to be acted upon is independent of and does not affect the pressure exerted by the springs 38 upon the respective stones. 105

Having described my invention I claim :

1. A device of the character described, comprising in combination, a supporting member, carrier members mounted upon the supporting member to be rotatable therewith and adjustable radially with relation thereto, said carrier members being formed with elongated sockets, abrading members secured within the sockets with provision for radial or outward movement, pressure plates hingedly supported longitudinally within the carriers and positioned to engage the inner sides of the 110 abrading members to one side of their central longitudinal axis, resilient means acting upon the pressure plates to impart yielding outward pressure to the abrading members and said abrading members being fitted 115 loosely within the sockets whereby they are tilted or inclined with reference to the surface acted upon, substantially as described. 120
2. A device of the character described comprising, in combination, a centrally posi- 125

tioned supporting shaft provided with spaced upper and lower collars, bearing shafts supported by collars in parallel relation, carrier members having upper and lower supporting arms pivotally mounted upon the bearing shafts, means for adjusting the position of the respective carrier members in unison, said means consisting of a rotatable adjusting member having a knurled peripheral surface and journalled upon the supporting shaft and pivotal link connections from said adjusting member to the respective carrier members, means for securing the adjusting member in its adjusted positions, said tray members being formed with elongated sockets, abrading members secured within the sockets with provision for radial or outward movement, pressure plates hingedly supported longitudinally of the stones within the carriers and resilient means acting upon the pressure plates to impart a yielding outward pressure to the stones, said stones being of rectangular cross-section and having a loose fit within the sockets and said pressure plates being adapted to engage the inner surfaces of the stones adjacent one longitudinal edge thereof whereby the stones will be tilted with reference to the surface acted upon.

Signed at Buffalo, in the county of Erie
30 and State of New York this 26th day of
April A. D. 1924.

WILLIAM FREDERICK EMERSON.
